UNITED STATES PATENT OFFICE.

HARRY A. LEWIS, OF BOSTON, MASSACHUSETTS.

EJECTOR FOR RIFLES.

1,335,063.

Specification of Letters Patent. Patented Mar. 30, 1920.

Application filed August 6, 1919. Serial No. 315,615.

To all whom it may concern:

Be it known that I, HARRY A. LEWIS, a citizen of the United States of America, and resident of the city of Boston, county of 5 Suffolk, and State of Massachusetts, have invented certain new and useful Improvements in Ejectors for Rifles, of which the following is a true and exact description, reference being had to the accompanying 10 drawings, which form a part thereof.

My invention relates to the construction of rifles, particularly to ejector mechanism, and has for its object to provide a simple, durable and inexpensive ejector mechanism, and 15 particularly to provide an ejector actuating spring which will not be liable to breakage.

My invention has been particularly devised for use in connection with rifles of the type known as the British Enfield or the 20 American modified Springfield, and it is illustrated in the drawings forming a part of this specification in this connection with the coacting parts of the breech mechanism of such a rifle.

25 The nature of my improvements will be best understood as explained in connection with the drawings in which—

Figure 1 is a horizontal section taken as on the line 1—1 of Fig. 2 and showing the 30 bolt stop and ejector mechanism.

Fig. 2 is a side elevation of the portion of the breech embodying the mechanism shown in Fig. 1.

Fig. 3 is a view generally similar to Fig. 35 1, but showing the bolt stop unsectioned.

Fig. 4 is a view generally similar to Fig. 1 showing the bolt in retracted position, and one of the lugs D³, to be hereafter described, in section.

40 Fig. 5 is a cross sectional view taken as on the line 5—5 of Fig. 4.

Fig. 6 is a perspective view of the bolt stop.

Fig. 7 is a perspective view of the 45 ejector.

Fig. 8 is a similar perspective view of the ejector and actuating spring as heretofore used in rifles of the kind referred to.

A indicates the solid material of the rifle 50 breech having formed in it an opening as indicated at A' through which extends the bolt stop and the active end of the ejector. At the rear end of this opening are formed the lugs A², A², and still farther in the 55 rear, as shown, is a circular opening indicated at A².

On the opposite side of the breech is formed the opening indicated at A⁴, through which the magazine communicates with the breech. B is the bolt, B' being the end 60 against which the cartridge abuts, B² a projecting lip which contacts with one portion of the cartridge rim. The upper part of the stop lug on the bolt on which the lip B² is formed, is grooved as indicated at B³ 65 for the passage of the active end of the ejector. B⁴ is a groove formed in the body of the bolt for the reception of a ring to be described. C is a block having formed on it the finger C', which engages the rim of the 70 cartridge, and rearwardly of said finger another finger C² which projects into a groove B⁵ formed in the bolt B. The block C is secured to a bolt C³ which moves in a slot formed in the breech frame, and, as 75 shown, has secured to it an inwardly projecting shoulder C⁴ to which is secured a ring C⁵, secured in turn in the groove B⁴ of the bolt. D is the bolt stop formed with an inwardly extending stop finger D' and with 80 pivot perforations, as indicated at D², at its rear end. This bolt stop, which is best shown in Fig. 6, is formed with lugs as indicated at D³, D³, the slot D⁴ separating such lugs, and it is also formed with a projecting ledge D⁵ to afford a grip for raising 85 it. E is the pivot on which the bolt stop is secured, which extends through the perforations in the lugs A². F is the ejector which, as shown, is also pivoted on the pivot pin E, 90 which passes through a perforation F' in its rear end. F² is a projecting lug or camlike shoulder formed on the ejector near its pivoted end for purposes to be hereafter explained. G is a spring rest having a projecting pin G' which extends into the perforation A³, and formed, as shown, with transverse slots G² and G³ in its head. As 95 shown in the drawings this device G serves not only as a spring rest but also has attached to it a sight rod H, carrying a sight H' at its end, and which can be folded down, as shown in Fig. 2, and thrown up into active position by turning the rest G through an angle of 90°. I is a plate 100 spring having downwardly projecting lugs I', I', which engage on the lugs D³ of the bolt stop, as indicated in the drawings, the rear end of the spring resting in a groove of the spring rest G, and pressing against 105 such spring rest acting to keep the bolt stop in the position shown in the drawings.

In all particulars shown in the drawing, with the exception of the formation of the shoulder F^2 on the ejector, the rifle mechanism is that of the well known Enfield rifle and is not my invention. As heretofore constructed, such rifles have been provided with ejectors constructed as shown in Fig. 8 of the drawing, and in which a spring tongue F^3 is sawed out of the material of the ejector 10 and in assembled relation presses against the spring I with the result of pushing the active end of the ejector downward. This construction has proved defective for the reason that a great many of the ejector 15 springs are broken in manufacture and a great many break in use. In my construction in place of using a spring such as F^3 I form the camlike shoulder F^2 on the ejector bar of such shape and dimensions that 20 it will press against the spring I, which spring is thereby given the double function of holding down the bolt stop and of exerting the necessary downward pressure upon the active end of the ejector bar. 25 It will be understood that when the bolt is in advanced position, as shown in Figs. 1, 2 and 3, the ejector is pressed upward and held in the position indicated in Figs. 1 and 3. When the bolt is retracted the active end 30 of the ejector passes down through the slot B^3 and striking the rim of the cartridge throws it out of the opening formed in the breech for that purpose, the final position of the ejector in the rearward movement of 35 the bolt being shown in Fig. 4.

Having now described my invention, what I claim as new and desire to secure by Letters Patent, is:

1. In a rifle, the combination of a pivoted retractable bolt stop and a spring holding 40 the stop in active position, with an ejector pivotally supported at its non-active end and formed with an unyielding shoulder bearing against and acted upon by the bolt stop spring. 45
2. In a rifle, the combination of a pivoted retractable bolt stop and a spring holding the stop in active position with an ejector pivotally supported on the bolt stop pivot at its non-active end and formed with an 50 unyielding shoulder bearing against and acted upon by the bolt stop spring.
3. In a rifle, a bolt stop pivotally supported on the rifle breech, in combination with a plate spring secured to the bolt stop, 55 a support for the free end of the spring at the rear of the pivotal support and an ejector also pivotally supported on the breech and formed with an unyielding shoulder bearing against the plate spring. 60
4. In a rifle, a bolt stop pivotally supported on the rifle breech in combination with a plate spring secured to the bolt stop, a support for the free end of the spring at the rear of the pivotal support and an ejector also pivotally supported on the breech 65 on the bolt stop pivot and formed with an unyielding shoulder bearing against the plate spring.

HARRY A. LEWIS.
